UNITED STATES PATENT OFFICE.

ALEXANDER M. SCHNEIDER, OF NEW YORK, N. Y., ASSIGNOR TO G. SPERLING, OF NEW YORK, N. Y.

UNDERGARMENT.

Application filed July 13, 1926. Serial No. 122,054.

This invention relates to undergarments, and more particularly to a form of undergarment having a more or less closely fitting body or trunk portion with closed crotch, 5 and enlarged loosely draped leg portions.

The objects of this invention include the provision of a durable improved undergarment, such as of the step-in-chemise type, of pleasing appearance, which will be comfortable and convenient in use, and which may be manufactured in quantities at a low cost.

Further and more specific objects, features and advantages will more clearly appear 15 upon reference to the following specification taken in connection with the accompanying drawings which serve to describe and illustrate the invention in certain of its preferred embodiments.

20 In the drawings:—

Fig. 1 is a front view illustrating a garment embodying the invention in one of its forms as applied to the wearer;

Fig. 2 is a side view of the same;

25 Fig. 3 is an enlarged back view of the garment alone;

Figs. 4, 5 and 6 are developed views of the several parts comprised in the garment of Fig. 3.

30 Figs. 7, 8 and 9 are front, side and back views respectively of another form of garment embodying the invention, and showing the garment as applied to the wearer;

Fig. 10 is an enlarged front view of the 35 same garment alone;

Figs. 11, 12 and 13 are developed views of the several parts comprised in the garment of Fig. 10; and,

Fig. 14 is a view similar to Fig. 13 but 40 illustrating a slightly modified construction of the part shown.

Referring to the drawings, the garment shown in Figs. 1 to 6 may comprise front and back body portions which may both be 45 of the general shape of the part 20 shown in Fig. 4. Two of these portions preferably are stitched as at 21 and 22 along the sides of the garment to form the trunk or body of the garment. The upper edges may be suitably hemmed at 23 and shoulder straps as at 24 may be attached thereto. If desired reinforcements as at 25 may be applied at the 50 armpits.

At the lower extremities 26^a of the parts

20 an elongated four sided crotch piece 26 55 may be secured which is preferably of double thickness or reinforced. Upwardly diverging leg openings are provided at the straight cut edges 27 and 28 (see Fig. 4) which openings extend to points at the sides 60 of the garment substantially at the waistline. At these openings flounces 29 and 30 comprising tubular leg portions are stitched. Each of these flounces may be of the general 65 shape of the part shown in Fig. 5 which is 65 a substantially quadrilateral member except that it has one of its sides cut away to provide a substantially semicircular edge 31 for attachment to the straight cut edges 27 and 28 on the body portions. Also portions at 70 32 on the semicircular edge are secured to the arcuate side edges as at 33 on the crotch piece 26. The upwardly convergent side edges 34 and 35 of the flounces 29 and 30 may be brought together for forming the 75 seam 36 (see Fig. 2) at the side of the garment and in alignment with the side seam of the body portion. The flounce pieces may be cut with generally horizontal lower edges 80 as at 37 so that if desired, in the finished garment the lower edges will extend uniformly down to a level approximately at the knees.

In this construction it will be noted that the body portion or trunk part of the garment, if desired, may be made substantially 85 form-fitting, whereas the enlarged hip and leg portions are uniformly and loosely draped. It has been found that provision of the straight cut leg openings on the body portion joined to the semi-circular cut edges 90 of the flounces makes this result possible without the use of patterns of complicated outline. Each of the patterns is made up of substantially straight lines and arcs of 95 circles. Accordingly, the parts may be accurately and quickly cut by inexpensive labor. These advantages are also accompanied by an improved appearance in the garment since the body portions 20, together with the crotch piece 26, are joined to the 100 flounces in this simple manner substantially along the upper line of the hips, such line forming a continuous regular curve from front to back of the garment when worn. The body portion and crotch piece 105 are devoid of irregular surfaces and sharp protruding seams and are designed to comfortably conform to the wearer in a manner

to retain the garment in normal position, yet the loosely draped leg portions permit free movement and, although of substantial length, may when necessary be drawn to one side, since the garment has a closed crotch.

In making the garment two body portions 20 of corresponding size may be first stitched together along the sides, as at 21. The upper edges 23 may then be hemmed 10 and the shoulder straps 24 and reinforcements 25 applied. The lower extremities 26^a may then be stitched to the ends of the piece 26. The flounce pieces which have been cut as above described may have their 15 edges 34 and 35 first stitched together to form the tubular leg portions and are then stitched at the leg openings in the body portion of the garment, care being taken to allow the flounce pieces to be uniformly 20 draped, thus permitting the leg portions to hang straight downwardly to a horizontal line adjacent the knees.

Figures 1 through 6 illustrate the invention as applied to a full length garment. 25 Reference will now be had to Figures 7 through 14 which illustrate the invention as embodied in a "step-in" garment extending only up to the waistline.

In this design of garment the trunk portion comprises two side pieces or gores 38 and 39 stitched together at the center of the front of the garment as indicated at 40 and also stitched together at the center of the back of the garment for a short 35 distance as indicated at 41 (see Fig. 9). The lower side edges of these gores are also stitched to a crotch piece 42 which extends to a point 43, a substantial distance up the back and also to a point 44, a lesser distance 40 up the front of the garment. Arcuate side edges as at 45, (see Fig. 9), are formed on the piece 42 corresponding to the arcuate edges 33 of the crotch piece 26 in the garment above described. Each of the gores 38 and 39 may be cut from a pattern shaped 45 substantially as indicated in Fig. 11. It will be noted that the side edges 46 and 47 of this pattern are substantially straight and parallel except that at 48 the upper 50 corner of the piece is cut at an angle for a substantial distance down the back of the garment. Two corresponding edges 48 on the gores 38 and 39 are stitched together to form the seam 41 above referred to. The 55 cutting of this edge at the angle indicated permits this seam to be located substantially in alignment with the seams at the side of the point 43 on the crotch piece when the garment is worn, thus insuring a good fit 60 without bulging or wrinkling of the parts joined at this area. The upper edges as at 49 of the gores 38 and 39 may be cut substantially straight to provide a straight 65 waistline. The lower edges of the gores, however, are preferably cut away in the

shape of a shallow straight sided V as indicated at 50 (see Fig. 11). The apex of the V is designed to be positioned at the sides of the hip portions of the garment. The upper edges of the gores may be suitably hemmed if desired as at 51 to enclose 70 an elastic band in the conventional manner.

After the parts as thus far described are stitched together, upwardly diverging leg openings will result having substantially 75 straight cut edges (except for the crotch piece) formed by the V cut edges 50. These openings extend up the sides of the garments to points close to the waistline. Leg portions as at 52 may be provided which 80 are of a shape generally similar to that of the flounces of the garment above described. A pattern for such a flounce is shown in Fig. 12. A segmental portion of the upper edge is cut away to provide an arcuate or 85 semicircular attaching edge 53 corresponding to the edges 31 and 32 of the garment above described. Upwardly convergent side edges 54 and 55 are provided and are 90 designed to be stitched together to form the tubular leg portions as will be readily understood. A generally horizontal lower edge 56 is formed on the flounce pieces so 95 that in the finished garment the lower edges will extend uniformly down a substantial distance to approximately knee height if desired. Figs. 7, 8 and 9 which 100 show the garment as worn, will serve to best illustrate these horizontally cut lower edges.

The crotch piece as shown in Fig. 13 is preferably of double thickness or otherwise reinforced. In Fig. 14 a crotch piece 57 of a slightly modified form of construction is 105 illustrated. In this form the front and middle portions of the piece are made of double thickness or reinforced as far as a seam 58, but from this seam on up the back of the garment a single thickness is used 110 forming the pointed area 59. Ample reinforcement is thus provided in a simple manner without materially adding to the weight of the garment and without adding complications to the manufacturing process.

It will thus be seen that in a garment of 115 this design just as in the full length type above described, the body or trunk portions may be made substantially form-fitting while the enlarged hip and leg portions are loosely uniformly draped. The advantages 120 above referred to of durability, comfort and convenience are therefore also available with this design.

While the invention has been described 125 in detail with respect to certain particular preferred and satisfactory examples, it will be understood by those skilled in the art after understanding the invention that various changes and modifications may be made 130 without departing from the spirit and scope

of the invention and it is intended therefore in the appended claims to cover all such changes and modifications.

What is claimed as new and upon which it is desired to secure Letters Patent of the United States is:

1. A combination undergarment comprising a substantially form fitting body portion with a closed crotch and leg openings diverging therefrom upwardly to points at the sides of the garment substantially at the waistline, and flounces comprising enlarged leg portions of tubular form secured at said openings, each of said flounces being when developed a substantially quadrilateral member but with one side cut away to provide a substantially semicircular edge for attachment at one of said leg openings, the two side edges next adjacent said semi-circular edge being stitched together along the side of the garment in forming the tubular leg portion.
2. An undergarment comprising front and back body portions stitched together along the sides of the garment and secured at their lower ends by a reinforced crotch member, and substantially knee length enlarged closed hip and leg portions secured to said body portions and crotch member, said body portions having upwardly diverging substantially straight edges and said leg portions having when developed substantially semicircular concave edges for joining said straight edges, whereby the body portions may be substantially form-fitting while the enlarged hip and leg portions are uniformly and loosely draped.
3. The method of making a closed crotch undergarment which comprises stitching front and back body portions together along the sides of the garment, securing the lower ends of said portions to a crotch piece, providing substantially quadrilateral pieces cut with upwardly converging side edges, cutting segments from the upper edges of said quadrilateral pieces to provide arcuate edges, securing said converging side edges together at the sides of the garment to form downwardly flared tubular leg portions,

and stitching said arcuate edges to the sides of the crotch piece and to said body portions with the flared leg portions uniformly draped.

4. A closed crotch undergarment comprising a body portion and leg portions of substantial length joined thereto, the body portion having upwardly diverging straight cut leg openings, the upper leg portions being cut away to provide arcuate concave edges joining said straight cut openings whereby the leg portions may be uniformly loosely draped while the body portion is closely conforming.

5. An undergarment comprising a body portion with a closed crotch and leg openings diverging therefrom upwardly to points at the sides of the garment substantially at the waistline, and flounces comprising enlarged leg portions of tubular form secured at said openings, each of said flounces being when developed a substantially quadrilateral member but with one side cut away to provide a substantially semicircular edge for attachment at one of said leg openings, the two side edges next adjacent said semicircular edge being stitched together along the side of the garment in forming the tubular leg portion.

6. An undergarment comprising two body portions stitched together along opposite sides of the garment and secured at their lower ends by an elongated crotch member having arcuate side edges, and enlarged closed hip and leg portions secured to said body portions and crotch member, said body portions having leg openings with upwardly diverging substantially straight edges and said leg portions having when developed substantially semicircular concave edges for joining said straight edges and the arcuate edges of said crotch piece, whereby the body portions may be substantially form-fitting while the enlarged hip and leg portions are uniformly and loosely draped.

In testimony whereof I have signed my name to this specification.

ALEXANDER M. SCHNEIDER.
